PORTABLE BATHTUB

Odie Putnam Galt, Canton, Ga.

Application June 11, 1937, Serial No. 147,738

3 Claims. (Cl. 4—185)

This invention relates to a portable bathtub designed primarily for use in bathing small children.

An object of the invention is to provide a simple, compact and efficient device of this character which can be set up for use upon an ordinary porcelain tub where it will be held securely while in use, the construction being such that, after the device has been used, it can be collapsed and stored in a small space.

A further object is to provide a device of this character adjustable so as to be supported upon bathtubs of different sizes.

Another object is to provide a device which serves also as a table for holding such articles as may be found necessary for use in washing or dressing an infant.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a bottom plan view of the device opened out for use.

Figure 2 is a transverse section on the line 2—2, Figure 1, a portion of a supporting bathtub being shown in section and a smaller tub forming a part of the present invention being also shown in section and in position.

Figure 3 is a section on line 3—3, Figure 1.

Figure 4 is a similar view showing the frame of the device folded for storage purposes.

Referring to the figures by characters of reference 1 designates a frame, preferably rectangular, and provided with a suitable top 2 secured thereon and formed with an opening 3. This opening is preferably located adjacent to one side of the frame so as to leave a considerable area between the opening and the opposite side of the frame for use as a table, this area being indicated at 4. The frame is divided into two sections along a line extending transversely across the opening 3, as indicated at 5, these sections being joined by hinges 6 so located as to allow the sections of the frame to fold together when not in use, and as shown in Figure 4. When thus folded the opposed sections of the frame can be held against relative movement by

any suitable means, such as a hook 7 carried by one of the sections and detachably engaging a pin 8 on the other section.

The frame is so proportioned as to extend transversely across and rest upon the upper edges of an ordinary porcelain bathtub B, as shown in Figure 2. In the bottom of the frame are formed grooves 9 in which are located slides 10 having slots 11 in which are located clamping bolts 12 or the like. Each slide has a jaw 13 extending downwardly therefrom. Normally these slides are located between the opposed sides of the tub B when the present invention is placed on the tub and it is thus possible to adjust the slides relative to each other in order to bring the jaws 13 against the inner surfaces of the tub B so as to prevent the frame 1 from sliding out of position on the tub. Thus the device can be adjusted for use on tubs of different widths.

The opening 3 is of such size and shape as to receive a small tub or water container 14 such as commonly used for bathing infants. This container has an outturned flange 15 at its upper edges adapted to bear downwardly on the top of the device so that the container thus will be supported in proper position while the device is in use. The area indicated at 4 can be used for supporting various articles necessary when bathing or dressing an infant.

When it is not desired to use the device the container 14 is lifted out of position and the two opposed sections of the frame are folded together as shown in Figure 4 after which they can be fastened and stored away with container 14 until again needed.

What is claimed is:

1. A device of the class described adapted to be supported on a bathtub, said device including a frame, a top secured thereto having an opening, said frame and top being divided into opposed sections, hinges joining the sections, a water container insertable into the opening and engaged and supported by the top, an adjustable means carried by the bottom of the frame for engagement with opposed sides of the supporting tub to hold the frame against displacement relative to said tub.

2. A device of the class described comprising a frame, a top secured thereon having an opening, said frame and top being separated into two sections, hinges connecting said sections for folding one upon the other in one direction only, a water container insertable into the opening to hold the sections against folding, said top constituting means for engaging and supporting the container.

3. A device of the class described comprising a frame, a top secured thereon having an opening, said frame and top being separated into two sections, hinges connecting said sections for folding one upon the other in one direction only, a water container insertable into the opening to hold the sections against folding, said top con-

stituting means for engaging and supporting the container, and means adjustably mounted on the bottom of the frame for engagement with opposed walls of a supporting tub or the like to hold the device against displacement relative to said supporting means. 5
